[57] CLAIM

The ornamental design for fancy light covers, as shown and
described.

DESCRIPTION

FIG. 1 is a front elevational view of fancy light covers, my
new design;

FIG. 2 is a rear elevational view thereof;

FIG. 3 is a left side elevational view thereof;

FIG. 4 is a right side elevational view thereof;

FIG. 5 is a top elevational view thereof;

FIG. 6 is a bottom elevational view thereof; and,

FIG. 7 is a front elevational view thereof; showing the fancy
light cover of the invention over the light fixture, the light
fixture being in phantom.
